GARTER BELT

Irving Kaldor, San Francisco, Calif.

Application April 7, 1947, Serial No. 739,825

1 Claim. (Cl. 2—306)

1

The invention, in general, relates to feminine undergarments and more particularly relates to an improved garter belt affording support for the abdomen and hips without likelihood of chafing the skin.

Heretofore in the art, numerous types and styles of garter belts have been devised ranging from the single strip for encircling the waist and having depending elastics with garter buckles, to the wider, girdle-like elastic bands. Many of these prior constructed garter belts are disadvantageous not only from the annoyance and discomfort standpoint but also because of their inability to remain in position on the body of the wearer in that they become folded or otherwise displaced during use particularly in walking. Other disadvantages, such as expensiveness and inconvenience of manufacture, have rendered many of these prior garments undesirable and unsalable.

A primary object of the present invention is to provide an improved garter belt affording a snug fit about the hips and abdomen for retaining the natural contours of the body, and affording retention of hose in place at all times.

Another object of my invention is to provide an improved garter belt of the indicated nature which is additionally characterized by a construction which avoids all likelihood of chafing of the skin, and which affords a soft comfortable garment admirably suited for close contact with the body.

Another object of the invention is to provide an improved garter belt of the aforementioned character which is relatively simple to assemble and produce, bringing manufacturing costs to a minimum.

Other objects of the invention, together with some of the advantageous features thereof, will appear from the following description of a preferred and a modified embodiment of the invention which are illustrated in the accompanying drawings. It is to be understood that I am not to be limited to the precise embodiments shown, nor to the precise arrangement of the various parts thereof, as my invention, as defined in the appended claims, can be embodied in a plurality of forms.

Referring to the drawings:

Figure 1 is a perspective view of a preferred embodiment of the invention, as viewed from the front thereof.

Figure 2 is another perspective view of the preferred embodiment of the invention, as viewed from the back thereof.

2

Figure 3 is a perspective view of a modified embodiment of the invention, as viewed from the front thereof.

In its preferred form, the improved garter belt of my present invention preferably comprises a sheet of cloth partially encircling the body, a piece of lace material spanning and connected to the lateral extremities of said cloth sheet; the edges of said piece of lace material being unselvedged, and elastic strips depending from said cloth sheet and said piece of lace material at the back and front of the garment for fastening hose thereto.

As particularly illustrated in Figures 1 and 2 of the annexed drawings, the improved garter belt of my present invention includes a pair of sheets of cloth 11 which partially encircles the body about the hips of the wearer and which have their front side edges preferably cut on a bias as specifically depicted in Figure 1 of the drawings; each of such sheets 11 preferably being extended at the back of the garment from their bottom edges and on the rear portions thereof to afford cloth extensions 12 and 13 which fit the backs of the thighs of the wearer. At the back of the cloth sheets 11, I provide a joiner strip 14 of elastic webbing which is detachably connected centrally of its side edges, conveniently by means of hooks and eyes, and which is connected to the cloth sheets by attaching the side edges of the joiner web to the rear edges of the sheets. As shown, the belt is provided with a pair of elastic strips 16 and 17 depending from the portions 12 and 13 of the sheet with garter buckles and tabs 31 fastened to the lower extremities of such elastic strips.

In accordance with my invention, I provide a piece or width of relatively soft material, preferably lace, for joining the front side edges of the cloth sheets 11 to complete the belt for entirely encircling the body at approximately the waistline. The width or piece of soft material is designated generally by the reference numeral 21 in the annexed drawings and it is preferably cut to the shape depicted to afford two slanting portions 22 and 23 at the sides thereof and generally conforms to the shape of the abdomen at the sides of the body. The piece of lace 21 conveniently is stitched to the front side edges of the cloth sheets 11 and, to reinforce the same at the top, I provide and attach by means of stitching a flat strip of tape 24 across the inside top of the lace insert. Moreover, a pair of spaced tapes 26 and 27 are sewn vertically from

top to bottom of the lace piece 21 to reinforce the same in a vertical direction. However, in order to insure that no chafing of the skin can occur by the rubbing action of the garment at the abdomen or thighs, the edges of the lace piece 21 are left unselvedged and there is thus presented to the skin a yielding soft garment portion. To complete the belt, I provide a pair of elastics 28 and 29 at the front thereof and preferably extending from the tapes 26 and 27, each of which elastic strips carry a hose clasp 31 for supporting hose.

In view of the provision of the short elastic webbing 14 at the back of the garment, it is clear that the belt of my present improvement adjustably fits the body and permits of some expansion during the use thereof. Moreover, the soft material such as the lace piece 21 at the front of the improved belt affords a garment that is yielding at the front and which does not chafe the skin or otherwise render the skin sore from the normal rubbing action of the garment on the skin during walking. It is to be understood, of course, that the elastic strips 16, 17, 28 and 29 which all carry hose clasps 31 also are provided with adjusting links for shortening or lengthening such strips to accommodate various sizes of persons.

In Figure 3 of the accompanying drawings, I have illustrated a modified embodiment of the present invention which is in all respects similar to the embodiment of Figures 1 and 2 except that the cloth sheets 11 are replaced by elastic webbing 10 and the joiner web insert 14 of the preferred embodiment is dispensed with since the elastic webbing 10 will take care of required expansion and adjustment to the body.

It is to be understood that the appended claim is to be accorded a range of equivalents commensurate in scope with the advance made over the prior art.

I claim:

A garter belt comprising a pair of cloth sheets; said sheets being adapted partially to encircle the body about the hips of the wearer, a cloth extension integral with each sheet of said pair of sheets and depending from the bottom edges of each of said pair of sheets at the rear thereof; said extensions being adapted to overlie the rears of the thighs of the wearer, a joiner web strip detachably connected together centrally of its side edges and connected at its side edges to the rear side edges of said cloth sheets; said joiner web strip being adapted to be disposed at the back of the wearer, a continuous unobstructed lace sheet attached at its side edges to the front side edges of said cloth sheets; said lace sheet having slanting portions at the sides thereof and being adapted to overlie the abdomen of the wearer, elastic strips connected to and depending from said cloth extensions, a pair of reinforced tapes attached to said lace sheet in spaced relationship and extending from the top edge to the bottom edge of said lace sheet; elastic strips connected to and depending from said tapes and hose clasps on all of said elastic strips for supporting hose on the belt.

IRVING KALDOR.
